Thurston & Bates

UNITED STATES PATENT OFFICE.

GEORGE D. CLAFLIN, JR., OF TOLEDO, OHIO, ASSIGNOR TO THE AMERICAN RAIL JOINT AND MANUFACTURING COMPANY, OF CLEVELAND, OHIO.

RAIL-CHAIR.

SPECIFICATION forming part of Letters Patent No. 606,515, dated June 28, 1898.

Application filed December 6, 1897. Serial No. 660,909. (No model.)

To all whom it may concern:

Be it known that I, GEORGE D. CLAFLIN, Jr., a citizen of the United States, residing at Toledo, in the county of Lucas and State of Ohio, have invented certain new and useful Improvements in Rail-Chairs; and I do hereby declare the following to be a full, clear, and exact description of the invention, such as will enable others skilled in the art to which it appertains to make and use the same.

The object of my invention is to provide a cheap chair for connecting and preserving the relative positions of a parallel car-rail and guard-rail of railway-tracks.

This invention consists in the construction and combination of parts shown and described, as pointed out definitely in the claims.

In the drawings, Figure 1 is a sectional end view of my improved chair in use. Fig. 2 is a side elevation thereof, and Fig. 3 is a plan view of the chair.

The chair is composed of three members—to wit, the outer member A, the inner member B, and the intermediate or spacing member C. These three members are constructed as and for the purposes as follows:

Each of the two members A and B consists of a base and a body, the construction of which in detail will be presently explained. The proximate edges of the bases overlap and are provided with interlocking tongues a^4 b^4 , which lie at a slight angle to the length of the members, whereby the endwise movement of either member relative to the other causes a slight lateral movement of said parts toward each other.

Upon the top of the base of the member A are formed flat horizontal seats a' a^2 , of which the former is near the outer edge of the base and is adapted to support the foot of the guard-rail D. The other seat a^2 is near the inner edge of said base and is below the plane of the seat a' . On the base of the member B is formed a flat horizontal seat b^2 , which when the two members interlock, as described, is in the same plane with the seat a^2 , these two seats being adapted to support the foot of the car-rail E.

The body a^3 of the member A rises from the base outside of the seat a' and extends inward and then upward, being shaped and proportioned so that it will bear upon the top of the rail-foot, which rests upon the seat a' , while its upper edge bears against the under side

of the ball of said rail. The body b^3 of the member is similarly shaped, so as to bear upon the foot of the rail, which rests upon the seats a^2 b^2 , while its upper edge bears against the under side of the ball of said rail.

The intermediate member C consists of a base c , two sides c' c^2 , and, preferably, strengthening end pieces c^3 . This member lies between the two rails D and E. Its base is shaped to fit upon the feet of the said two rails when the upper edges of the sides engage beneath the two rail-balls.

A lug a^5 is formed on the inner face of the vertical part of the body, extending inward therefrom. This lug passes through a hole in the web of the guard-rail and into a hole in the proximate side c' of the member C. This lug prevents the endwise movement of the member A when the member B is being drawn endwise to cause the clamping action of the chair members upon the rail.

Having described my invention, I claim—

1. A rail-chair consisting of the members A and B, having oblique interlocking tongues, the member A consisting of a body a^3 , and a base having the two flat seats a' a^2 in different planes, the member B consisting of a body and a base having a flat seat b^2 which is in the same plane with the seat a^2 , combined with an intermediate member which fits between two rails resting upon the seats a' and a^2 b^2 , and bears against the feet and balls of said rails, substantially as specified.

2. A rail-chair consisting of the members A and B, having oblique interlocking tongues, the member A consisting of a body a^3 and a base having the two flat seats a' a^2 in different planes, and having an integral lug projecting from the inner face of the body and adapted to pass through a hole in the web of the proximate rail and into a hole in one side of the member C, the member B consisting of a body and a base having a flat seat b^2 , which is in the same plane with the seat a^2 , combined with an intermediate member which fits between two rails resting upon the seats a' and a^2 b^2 , and bears against the feet and balls of said rails, substantially as specified.

In testimony whereof I affix my signature in presence of two witnesses.

GEORGE D. CLAFLIN, JR.
